UNITED STATES PATENT OFFICE.

HARRY GUY ANDERSON, OF NEW YORK, N. Y.

KEYLESS LOCK.

Application filed January 8, 1926, Serial No. 80,010. Renewed April 25, 1928.

This invention relates to improvements in keyless locks and more particularly to locks designed for use on the vestibule doors of railway cars and on the doors of railway car 5 toilets, although it is capable of a variety of other uses also. One object is to provide a lock that will serve automatically to keep the doors locked while the train is in motion but that will permit them to be unlocked and 10 opened when the train is standing still.

A further object is to provide a lock of this type that is positive and efficient in operation and durable in use. With the foregoing and other objects in view the invention consists in 15 the combination and arrangement of parts to be hereinafter fully described, pointed out in the appended claims and illustrated in the accompanying drawings which form a part of this application and in which—

20 Fig. 1 is a fragmentary view of the vestibule door of a railway car provided with the lock.

Fig. 2 is a cross section on line 2—2 of Fig. 1, illustrating the interior construction 25 of the lock.

Fig. 3 is a cross section on line 3—3 of Fig. 2.

Fig. 4 is a fragmentary perspective view of the lock casing and interior.

20 Fig. 5 is a view in elevation and partly in section of the lock casing and interior mechanism.

Fig. 6 is a view of Fig. 5 with the adjustable parts in an altered position.

35 Fig. 7 is a view of Fig. 5 showing a third position of the movable parts.

Fig. 8 is a perspective view of the cam with its integral sleeve.

Fig. 9 is a vertical section on line 9—9 of 40 Fig. 3.

Fig. 10 is a view similar to Fig. 5 but showing a modified form of lock.

Fig. 11 is a view of Fig. 10 with the movable parts in altered position.

45 Fig. 12 is a view of Fig. 10 with the parts in a third position.

Like reference characters denote corresponding parts throughout the several views.

The present type of vestibuled railway cars 50 is provided with doors that are designed to be kept shut while the train is in motion and opened when the train is standing to permit loading and unloading of passengers. Quite frequently, however, a passenger will step to 55 the door while the train is in motion and open

the vestibule doors in order to get a better view of the scenery or to "cool off", to get fresh air or for other purpose. Not being accustomed to the roll and sway of the train, however, he may lose his balance in an unguarded moment or by the train rounding a curve he may be thrown from the platform out upon the right of way with the attendant probability of serious injury or death and at best with the practical certainty of thereby 60 "missing his train".

It is the purpose of the present invention to effectively guard against such occurrence and to this end the vestibule doors are provided with locks that can be opened only 70 when the train is standing or moving very slowly, say 15 miles per hour or less.

The lock comprises a casing having the side walls 1, 2, end walls 3, 4, a cover 5 having a recessed insert 6, and a base 7 formed likewise with a recessed insert 8. Secured to the wall 3 by fastening means 9 is the angular bracket 10 the upper end of which is pointed for disposal in the recessed lug 11 carried by the table 12, the top surface of which is beveled 75 toward its center, whereby the same is supported for oscillation within the lock casing. Secured to and depending from the under side of the table 12 are the straps 13, 13 that converge toward each other and between them support the weight 14 disposed beneath the pointed extremity of the bracket 10 so that the table is disposed horizontally 80 when not disturbed by motion or vibration from without. The table is of a diameter less than the distance between the walls 1, 2 in one direction and less than the distance between the walls 3, 4 in a transverse direction so that while it can rock or oscillate freely 85 upon its support it cannot become disengaged 90 therefrom.

A sleeve 15 extends transversely of the lock casing and through the walls 1, 2 and is open at one end, said sleeve carrying the sliding bolt 16, one end 17 thereof being diminished in diameter and disposed in the closed end of the sleeve 15 and encircled by an expansion coil spring 18 that abuts the shoulder formed upon the bolt at the junction of its large and small portions, said spring also abutting the closed end of the casing so that it yieldingly projects the free and concave end 19 of the bolt from the open end of the sleeve. The sleeve 15 is formed with the oppositely disposed perforations 20 which 100 105 110

are disposed in line with the perforations for the extensions 21 of the knobs 22, 23, one perforation 24 in the wall 3 for the knob extension 21 of knob 22 being shown in Fig. 9.

5 The said bolt 16 is formed with a large perforation 25 bridged only by the oppositely disposed strap-like portions 26, 27 and into said perforation the integral beveled portion 28 extends, the apex of the beveled portion 28 being disposed midway between the strap-like portions 26, 27. The shaft that connects the knobs 22, 23 comprises the shank 29 formed with a terminal head 30, a trough-like portion 31 semi-circular in cross section 10 and receiving the said head 30, and the threaded or grooved portion 32 upon which the knob 22 is received and secured through the medium of the screw 33. The trough-like portion 31 of the knob shaft extends through 15 the perforation 25 in the bolt and through the sleeve perforations 20 with its open side receiving the beveled portion 28 of the bolt as shown in Fig. 3 so that oscillation of the knob shaft in either direction will cause the lateral 20 edges of the trough-portion 31 to engage with the bevel 28 and retract the bolt thus disposing it entirely within the sleeve against the tension of the spring 18. A cam or dog 34 is secured by means of the pin 35 to the shank 29 contiguous to the head 30 and to one end of the trough-like portion 31 of the shaft.

Referring now to the lock as shown only in Figs. 1 to 9 inclusive the cover 5 is formed with a stop lug 36 that is disposed against the 25 side wall 2 just above a leaf spring 37 secured at one end to said wall 2 for engagement with the upper free end of an angular lever 38 fulcrumed upon a pin 39 that connects a pair of spaced lugs 40, 41 secured to the wall 2, said 30 pin extending through a perforation in the end wall 4 and being threaded to receive the retaining head 42. The said lever 38 is formed with an integral toe 43 which is disposed above the central point of the beveled 35 table 12 for engagement with a ball 44, freely disposed upon said table, when said table is stationary, said ball having then gravitated to the center of the table between the spaced guard pins 45, 45 which lie in a straight line 40 connecting the walls 1, 2.

A sleeve 46 is adapted for disposal freely upon the shank 29, said sleeve at one end being formed with the large cam 47 integral with the small segmental portion 48, said cam 47 carrying a pin 49 upon the face remote from the sleeve 46, said sleeve being adapted for passage through the knob-shaft-perforation in the casing wall 4 and being formed with a perforation 50, this end of said sleeve 55 being received into the extension 21 of the knob 23, said members being secured together by a screw passing into the said perforation 50 and through a perforation in the said extension 21. A pin 51 also carried by said 60 sleeve being spaced from the perforation 50

and being disposed upon the opposite side of the casing wall 4 with relation to the knob extension 21 is shown in Fig. 2.

When the sleeve 46 is in position upon the shank 29 the cam 47 is contiguous to the dog 34 so that said dog in its movement with said shank will engage with the pin 49. A coil spring 52 encircling the sleeve 46 has one end secured to the said pin 49 and its opposite end to a pin 53 in the casing wall 4. In operation 70 the bolt 16 is to be retracted by the knob 23 which is the inside knob as distinguished from the knob 22 which is located outside the door. When the train is running the vibration and sway motion is sufficient, unless the train is running at a speed of 15 miles per hour or less, to cause the table 12 to tilt thus causing the ball 44 to move about. The spring 52 serves yieldingly to retain the sleeve and cam 46, 47 in normal position illustrated in Fig. 5. One edge of the cam is now disposed against the stop lug 36 and it is engaged peripherally by the upper end of the lever 38. By now turning the knob 23 in one direction the sleeve, loose upon the shank 29, is rotated thus rotating the cam into the position shown in Fig. 7. The outer edge of the cam is now disposed in such position that the lever 38 may move away from the casing wall 2, the upper end of said lever being engaged by the portion 48 of the cam the movement of that member being arrested thereby before the pin 49, which is disposed in the path of the dog 34 can operatively engage said member. If an attempt is made to move the cam in the opposite direction it will ride into engagement with the lug 36 as shown in Fig. 5. Oscillation of the sleeve and cam by knob 23 now accomplish nothing. If the train is standing or running at so slow a speed that the ball 55 may center upon the table through gravity and on account of the horizontal position of the same the lever 38 will engage the ball and be supported or retained through such contact in upright position shown in Fig. 6. The knob 23 may now be turned and the sleeve and cam rotated causing the pin 48 to engage with the dog 34 and thereby rotate the shafts 29, 31, 32 thus retracting the bolt. When it is desired to hold the table against oscillation 105 so that the ball 44 may center upon the table even though the train is in motion use is made of a rod 54 that extends through the casing and is supported in the top and bottom thereof and provided with a lift lug 55 adapted, when the rod is raised slightly, to engage with one edge of the table to prevent oscillation thereof, said rod being secured against accidental withdrawal from the casing by means of the cotter pin 56.

In Figs. 10, 11 and 12 a modification is shown and this form of lock is adapted for use upon railway car toilet doors. In this instance it is desired to permit the door to be unlocked and opened only when the train is 110 120 125 130

motion and the ball 44 thereby disturbed from the table center. The shank 29' is provided with the dog A fast thereupon and the sleeve 46 and cam 47 are dispensed with. The knob 23 is used to open the door. A lever 38' formed with a cam head B is fulcrumed upon the pin 39', this head being of such size and weight it will normally cause the lever to gravitate toward the table 12 or into the position shown in Fig. 11 except at such time as said lever may be engaged by the dog A in which position it is yieldingly retained by the bolt spring 18. When the train is standing and the ball is centered upon the table the head B of the lever 38' will contact with said ball if the knob 23 is turned but by said ball said head is spaced above the table in such position as to prevent passage of the dog A thus effectually resisting rotation of the shank 29' or retraction of the bolt.

What is claimed is:—

1. In a keyless lock, a casing, a bolt slidably arranged in said casing, bolt actuating mechanism carried by said casing, a lever 25 fulcrumed to said casing and serving in one position to block operation of said bolt actuating mechanism, and delicately poised mechanism associated with said lever and normally disposed in horizontal position sensitive to vibration caused by exterior commotion whereby said lever is rendered operative or inoperative.

2. In a keyless lock, a casing, a bolt slidably arranged in said casing, bolt actuating mechanism carried by said casing, means adjustably associated with said bolt actuating mechanism whereby operation of the same may be blocked, and mechanism associated with said last named means and poised normally in a predetermined position and sensitive to exterior vibration communicated thereto whereby said means may automatically be rendered operative in the absence of said vibration and inoperative during the presence of said vibration.

3. In a keyless lock, for vehicles, a casing, a bolt slidably arranged in said casing, bolt actuating mechanism carried by said casing, means adjustably associated with said bolt actuating mechanism whereby operation of the same may be blocked, and mechanism as-

sociated with said last named means and poised normally in a predetermined position and automatically adjustable from normal position by motion of the vehicle to render the said means inoperative.

4. In a keyless lock, a casing, a pivotally supported element concave toward its center arranged within said casing, a ball free to move upon said element, a sliding bolt in said casing, a rotary shaft extending through said bolt and casing, a knob fast upon one end of said shaft, a dog fast to the shaft, a sleeve loose upon said shaft, a cam fast to one end of said sleeve and contiguous to said dog, a pin 60 carried by said cam for engagement with said dog, a knob fast to said sleeve, a lug carried by said casing for engagement by said cam, and an angular spring-pressed lever fulcrumed to said casing for engagement with 65 said ball when the same is centered upon said pivotally supported element and for engagement with said cam to arrest the operative movement of the same when said ball is disposed off center of said element.

5. In a keyless lock, a casing, a tilting table concave toward its center arranged within said casing, a ball movable upon said table, a bolt slidably arranged in said casing, bolt actuating mechanism carried by said casing operable only when said ball is in a predetermined position upon said table, said mechanism comprising a lever fulcrumed to said casing and capable of engagement with said ball, and means carried by said casing for positive engagement with said table to stabilize the same.

6. In a keyless lock, a casing, a tilting table concave toward its center arranged within said casing, a ball freely movable upon said table, a bolt slidably arranged in said casing, bolt actuating mechanism carried by said casing, a lever fulcrumed to said casing and capable of engagement with said ball, and delicately poised mechanism associated with said lever and in normal position being sensitive to vibration caused by exterior commotion whereby said lever is rendered operative or inoperative.

In testimony that I claim the foregoing as my own I have hereto affixed my signature.

HARRY GUY ANDERSON.
